CLAIM

The ornamental design for a shoe outsole, as shown and described.

DESCRIPTION

FIG. 1 is a bottom plan view of a shoe outsole showing our new design;

FIG. 2 is a rear elevational view thereof, the broken lines showing a shoe upper in FIGS. 2-5 being for illustrative purposes only and form no part of the claimed design;

FIG. 3 is a front elevational view thereof;

FIG. 4 is a right side elevational view thereof; and,

FIG. 5 is a left side elevational view thereof.

1 Claim, 2 Drawing Sheets Fig. 1.

Fig. 3.

Fig. 2.
